AGITATOR PADDLE

Prudie Dace, Fairview, Okla.

Application July 14, 1937, Serial No. 153,656

1 Claim. (Cl. 259—144)

The present invention relates to agitators or paddles for use in butter making or the like and has for its object to provide an article of this character which is simple and practical in construction, efficient in operation, strong and durable and otherwise well adapted for the purposes for which the same is intended.

Other objects and advantages reside in the details of construction and operation as more fully 10 hereinafter described and claimed reference being had to the accompanying drawing forming part hereof wherein like numerals refer to like parts throughout and in which:—

Figure 1 is a perspective view of the paddle and 15 Figure 2 is a fragmentary sectional view taken substantially along the line 2—2 of Figure 1. Referring now to the drawing in detail, wherein in for the purpose of illustration I have disclosed a preferred embodiment of the invention, the 20 numeral 5 designates a handle having a reduced end 6 which is inserted in an opening in a plate member 7. A wire brace member 8 has its opposite ends attached in spaced relation to one edge of the plate 7 by means of screws or the like 9, the intermediate portion of the brace being bent 25 to form an eye 10 secured to the handle by a screw eye 11 or the like. As clearly illustrated in Figure 1 of the drawing the arms of the brace diverge from the handle outwardly toward opposite sides of the plate to rigidly secure the plate 30 in a position transversely with respect to the handle.

The handle is secured to the plate adjacent one edge thereof and in its opposite edge the plate is 35 formed with a series of spaced openings 12

through which are threaded flexible strips of material 13 so that the opposite ends of the strips extend from opposite sides of the plate a substantially equal distance and the strips are secured in position against the removal from the plate by 5 stitching 14 passing through both of said end sections. The strips of material 13 constitute agitating elements which have one end freely disposed with respect to the plate and positioned in spaced parallel relation with respect to each 10 other.

By means of this construction a paddle or agitator is thus provided which affords a greatly increased area for stirring or agitating the substance being worked while at the same time reducing the resistance to which a rigid paddle is subjected.

It is obvious the invention is susceptible of changes in construction without departing from the spirit of the invention or the scope of the 20 appended claim.

Having thus described the invention what is claimed is:—

An agitator of the class described comprising a handle, a substantially rectangular plate secured to one end of said handle and positioned at right angles thereto, the lower edge of said plate being beveled and being provided with a plurality of openings, and flexible agitating members passing through said openings, the outer 25 ends of said agitating openings being free and the intermediate portions stitched together along the beveled edge of the plate to prevent displacement.

PRUDIE DACE. 35
